DESIGN FOR A LATCHING DEVICE

James Innes, Pelham, Lipman Cohen, New Rochelle, and Lee Spatz, Hempstead, N. Y., as signors to British-Makes, Inc., New York, N. Y., a corporation of New York

Application September 15, 1945, Serial No. 122,106

Term of patent 14 years

(Cl. D50—5)

To all whom it may concern:

Be it known that we, James Innes, Lipman Cohen and Lee Spatz, all citizens of the United States of America and residents of the city of Pelham, county of Westchester, State of New York, city of New Rochelle, county of Westchester, State of New York, and Hempstead, Nassau County, State of New York, respectively, whose post-office address is 1141 Broadway, New York, New York, have invented a new, original, and ornamental Design for a Latching Device, as shown, of which the following is a specification, reference being had to the accompanying drawing, forming part thereof.

Figure 1 is a face view of a latching device

showing our new design, the lock being in open position;

Figure 2 is a view of the opposite face of the latching device;

Figure 3 is a top plan view of the latching device, and

Figure 4 is a top plan view of the latching device in its closed or locked position.

We claim:

The ornamental design for a latching device, substantially as shown.

JAMES INNES.
LIPMAN COHEN.
LEE SPATZ.
